CLAIM

The ornamental design for a smart watch, as shown and described.

DESCRIPTION

FIG. 1 is a front perspective view of a smart watch showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an enlarged view of the delineated portion 9 in FIG. 1; and,

FIG. 10 is an enlarged view of the delineated portion 10 in FIG. 2.

The dashed broken lines in the figures depict portions of the smart watch that form no part of the claimed design. The dot-dot-dash broken lines in the figures delineating portions

(Continued)

of the claimed design that are illustrated in enlargements form no part of the claimed design.
